STRETCHING FRAME

Frank C. Osborn, Manchester, Vt.

Application September 14, 1939, Serial No. 294,850

5 Claims. (Cl. 45—130)

This invention relates to stretching frames, and more particularly canvas stretching frames, although it is adaptable to picture frames and to any other uses where there is a necessity of stretching sheet material whether of cloth, paper or other fabric. For the purpose of simplicity we will refer in this specification to stretching canvas since this is one of the uses to which my invention is most readily adaptable.

An object of the invention is to provide a stretcher in which canvas or other material may be simply and quickly stretched without permanently fastening the canvas in the frame.

Another object is to provide a stretching frame in which canvas may be placed and removed at will and in which the degree of tension placed upon the canvas may be simply and readily controlled. A great many materials, such as canvas, react to atmospheric conditions and it is essential that the tension thereon may be varied at will.

A further object is to provide a device of the character described which will be compact in form and adaptable to a number of canvases.

With these and other objects in view reference is had to the accompanying drawings, in which—

Fig. 1 shows a plan view of a canvas stretcher embodying my invention;

Fig. 2 is a sectional view taken on the line 2—2 of Fig. 1;

Fig. 3 is a sectional view taken on the line 3—3 of Fig. 1;

Fig. 4 is a sectional view taken on the line 4—4 of Fig. 1;

Fig. 5 is a cross-sectional view taken on the line 5—5 of Fig. 1;

Fig. 6 is a cross-sectional view taken on the line 6—6 of Fig. 1;

Fig. 7 is a cross-sectional view taken on the line 7—7 of Fig. 1;

Fig. 8 is a plan view in section of a modified form of my invention;

Fig. 9 is a cross-sectional view taken on the line 9—9 of Fig. 8.

I provide an outer frame 15, preferably made of metal such as Monel metal or steel, which would be light but strong in construction and which is best formed at an angle as shown in Fig. 3. An inner frame 16 is fastened to one end of the outer frame by the hinge 17. While I have shown my inner frame as made of U-shaped metal, it will be appreciated that this may be made of wood or any suitable material. The inner frame 16 fits within the outer frame 15.

On the outer frame 15 are a series of pins 18

adapted to register with holes 19 on the inner frame 16. The pins 18 may be welded to the outer frame 15, or as shown in Fig. 9, may be integral therewith. In order to hold the frame 16 within the frame 15 a latch 20 with a tongue 21 is pivoted at 22 to the frame 15. This latch 20 engages openings 23 in the frame 15 and 24 in the frame 16 to hold the frames in a closed position.

Mounted in the frame 16 are a plurality of guide members 30 in which are mounted sliding members 31. On the sliding members 31 are a plurality of cams 32 mounted at an angle to the longitudinal axis of the sliding members 31. On each of the sliding members 31 is mounted a handle 35. The handle 35 has an elongated slot 36 engaging a pin 37 on the member 31. The lower portion of the handle 35 has a rounded shoulder 25 and the edge 26 of the handle member 35 adjacent the rounded shoulder 25 contacts a wall 27. It will be apparent that when the handle 35 is moved outwardly to the full extent of the slot 36, the handle 35 may be folded into the frame due to the fact that the rounded shoulder 25 will pass the wall 27. However, when the handle 35 is moved inwardly, the edge 26 thereof engages the wall 27 and prevents the lowering or folding of the handle 35. It will thus be seen that when the handle is pushed inwardly, as shown in Fig. 4, the slide members 31 may be moved in either direction, but when the handle 35 is pulled directly away from the frame it may be pivoted downwardly out of the way, as shown in Fig. 7. The end 38 of the handle 35 engages a spring 39 on the sliding member 31 when the handle is out of use to prevent its falling outwardly.

I also provide a stretching frame 40 normally made of wood or some similar material. Mounted on the stretching frame 40 are a plurality of studs 41 placed on the stretching frame 40 by means of the plate 42 or by any other suitable means. The forward edge of the stretching frame 40 is beveled to form a shoulder at 43 to form a contact surface for stretching purposes, and the studs 41 are adapted to engage the inclined cam 32 so that when the sliding member 31 is pulled in one direction the cams 32 will exert pressure upon the studs 41 thus forcing the stretching frame 40 toward the front of the outer frame 15.

I have also provided springs 45 on the stretching frame 40 which are slidably held by screws 46 to the loop ends 47 of the springs 45. The springs 45 engage a screw 49 in the inner por-

tion of the frame 16 and tend to hold the stretching frame 40 rearwardly, that is, toward the rear of the frame 16, and to position the frame 40 within the frame 16 when the frame 16 is moved out of the outer frame 15. Thus it will be seen that the hinged unit formed by the frames 15 and 16 may be opened and the frame 16 bearing the stretching frame 40 moved on the hinge 17.

My invention avoids the necessity of hand stretching and fastening the canvas on a stretching frame similar to the frame 40 while the canvas is being painted, and makes it possible to stretch canvases for painting purposes and to remove them and substitute others before the painting is finished, if desired. Obviously the finished painting would be re-stretched on a permanent frame but my invention makes it unnecessary for the painter to perform this work until the canvas is finished. It will be noted that the painting surface of the canvas 50 is within the shoulder 43 of the frame 40 and that when the canvas is finished an unpainted portion of just the right dimensions is reserved for final stretching of the canvas on a regular stretcher frame with a slight excess to allow the use of canvas pliers.

In the operation of my invention the frame 16 is swung on the hinge 17 upwardly and away from the outer frame 15. This is done merely by opening the latches 20 and separating the frames. A canvas 50 is then placed in the outer frame 15 upon the pins 18. The frame 16 is then swung into place forcing the pins 18 through the canvas and the latches 20 swung into place to hold the frames 15 and 16 together. By swinging the handles 35 upwardly and dropping them so that the edge 26 thereof contacts the wall 27, the slide members 31 may be moved to increase the pressure of the inclined cam 32 against the studs 41 on the stretching frame 40. This forces the shoulder 43 against the canvas 50 at 51 and exerts an even pressure throughout the entire canvas. If it is desired to substitute another canvas, pressure is released by moving the handles 35 in the opposite direction opening the frame and removing the canvas 50 from the pins 18.

In the modified form of my invention shown in Figs. 8 and 9, a segmental quadrant 60 having teeth 61 is mounted at 62 on the stretching frame 40. A slide member 63 has a section with teeth 64 which engage the teeth 61. The slide member 63 has cam surfaces 65 which cam surfaces engage studs 66 mounted on the inner frame 16. The preliminary operation of the modified form is the same as that heretofore described, and the slide member 63 is moved by the operation of a handle 67 thus varying the pressure exerted by the cam surfaces 65 on the studs 66. In order to prevent the movement of the frame 40 within the frame 16, screws 70 are provided which engage projections 71 in a portion of the frame 16 to position the frame 40 within the frame 16 and to prevent its movement when the

pressure is changed. A strip of cardboard matting 72 or similar soft material may be placed on the pins 18 before placing the canvas thereon. While not necessary, this strip insures a better grip upon the canvas.

I claim:

1. In a device of the character described, an outer frame member, an inner frame member hinged thereto and adapted to rest within said outer frame member, means on said inner and outer frame members to position material to be stretched, a stretching frame mounted within said inner and outer frame members, studs on said stretching frame, members having cam surfaces slidably mounted on said inner frame member and engaging said studs, and means for moving said cam bearing members in and out of selective positions.

2. A device of the character described including an outer frame assembly, means for positioning material to be stretched in said outer frame assembly, a stretching frame positioned in said outer frame assembly, and means for forcing said stretching frame forwardly against the material to be stretched, said means including members having cam surfaces mounted on one of said frames, studs engaging said cam surfaces on the other of said frames, and means for moving said members bearing the cam surfaces with relation to the studs.

3. A device of the character described including an outer frame assembly, means for positioning material to be stretched in said outer frame assembly, a stretching frame positioned in said outer frame assembly, and means for forcing said stretching frame forwardly against the material to be stretched, said means including studs mounted on one of said frames and sliding cam surfaces engaging said studs, on the other of said frames.

4. A device of the character described comprising an outer frame, an inner frame hinged thereto at one end thereof, means for maintaining said frames in a closed position, additional means for positioning material to be stretched between said frames, a stretching frame resiliently mounted within said inner frame, means for forcing said stretching frame forwardly against the material to be stretched, said means including studs and slideable cam surfaces, and additional means for positioning said cam surfaces with relation to said studs.

5. A device of the character described comprising an outer frame, an inner frame hinged thereto at one end thereof, means for positioning material to be stretched between said frames, a stretching frame resiliently mounted within said inner frame, means for forcing said stretching frame forwardly against the material to be stretched, said means including studs and slideable cam surfaces, and operating handles to position said cam surfaces with relation to said studs.

FRANK C. OSBORN.
